UNITED STATES PATENT OFFICE.

CHESTER B. MILLS, OF EAST MCKEESPORT, PENNSYLVANIA, ASSIGNOR TO WESTINGHOUSE ELECTRIC & MANUFACTURING COMPANY, A CORPORATION OF PENNSYLVANIA.

CURRENT-COLLECTING DEVICE.

1,427,407.

Specification of Letters Patent. Patented Aug. 29, 1922.

Application filed November 26, 1918. Serial No. 264,235.

To all whom it may concern:

Be it known that I, CHESTER B. MILLS, a citizen of the United States, and a resident of East McKeesport, in the county of Allegheny and State of Pennsylvania, have invented a new and useful Improvement in Current-Collecting Devices, of which the following is a specification.

My invention relates to brush-supporting devices, being particularly adapted for use with current-collecting rings, and it has for its object to provide apparatus of the character designated that shall be simple and inexpensive in construction and in which the brush-adjustment shall be reduced to a minimum.

In the accompanying drawings, Fig. 1 is an end-elevational view of a portion of a dynamo-electric machine provided with current-collecting devices constructed in accordance with my invention; Fig. 2 is a detail plan view of an individual brush box showing the radial adjusting device also shown in Fig. 1, and Fig. 3 is a sectional view along the line III—III of Fig. 1 and showing the longitudinal adjusting device embodied in my invention.

Heretofore, in assembling dynamo-electric machines, it has been necessary to adjust the individual brushes with respect to the collector rings very carefully. By my invention, I reduce the amount of necessary adjustment to a minimum and, at the same time, produce a device wherein the brushes are both radially and longitudinally adjustable, and in which the parts are so designed as to be readily adapted for die casting and for ready assembly and easy inspection.

For a better understanding of my invention, reference may be had to the accompanying drawings in which I show a portion of a dynamo-electric machine 1 provided with an end bracket 2 having projecting arms 3 upon which a current-collecting device 4 is mounted. The current-collecting device 4 comprises an arcuate brush carrier 5 supporting a plurality of brush boxes 6. Each of the brush boxes 6 comprises a box structure 8 having side lugs 9 which are provided with slots 10 through which bolts 11 extend to attach the brush box to the carrier 5. Radial adjustment may be effected, as the collector rings wear down, by loosening the bolts 11, sliding the brush box toward the collector ring in a radial direction,

and again tightening the bolts. A brush 12 is mounted within the brush box 6 and is held in engagement with a collector ring 7 by means of a spring 13 that is separately mounted upon the brush carrier 5 by means of a bolt 14. The inner end of the spring 13 is fastened to a sleeve member 15 that surrounds the bolt 14 and is provided with a ratchet wheel 16 which is held in position by means of a pin or lug 17 projecting from the brush carrier 5. In order to adjust the pressure of the spring upon the brush, the bolt 14 may be loosened sufficiently to permit the sleeve 15 to be moved outwardly thereon until the ratchet wheel clears the end of the pin 17. The ratchet wheel may then be turned to effect the desired adjustment of spring pressure; after which it may be replaced, with one of its teeth in engagement with the pin 17, and be clamped in position by the bolt 14.

The brush carrier 5 is composed of good conducting material and is electrically connected to the brushes 12 by means of flexible shunts 18, as well as through the brush box 6, and is connected to an external circuit by means of terminals 19 welded upon the outer periphery thereof. The arms 3 of the end member 2 are provided with a plurality of longitudinally-extending pins 20, only one of which is shown, which support a plurality of brush carriers 5, 21 and 22 and are separated therefrom by insulating sleeves 23 and from each other by short insulating sleeves 24. The brush carriers may be longitudinally adjusted by means of a threaded nut 25 and a coacting threaded sleeve 26 that is mounted upon the pin 20 intermediate the sleeve 24 and the arm 3. When the desired longitudinal adjustment has been made, the carriers may be locked in position by means of a threaded lock nut 27, also mounted upon the sleeve 26, and a bolt 28 having threaded engagement with the other end of the pin 20.

It will be understood by those skilled in the art that, by my invention, I have produced a device which reduces the labor of adjusting the brushes of collector rings to a minimum and which is composed of parts that may be inexpensively constructed and are strong and durable.

While I have shown but one form of my invention, and described, in detail, but one application of the same, it will be obvious

to those skilled in the art that it is not so limited but is susceptible of various minor changes and modifications without departing from the spirit thereof, and I desire, 5 therefore, that only such limitations shall be placed thereupon as are imposed by the prior art or are specifically set forth in the appended claims.

I claim as my invention:

- 10 1. In a current-collecting device, a collector ring, a brush carrier adapted to hold a plurality of brushes in engagement with said ring, and means for longitudinally adjusting said carrier and said brushes as a unit, and means for radially adjusting said individual brushes.
- 15 2. In a current-collecting device, a plurality of collector rings, a plurality of arcuate-shaped brush carriers of conducting

material, each adapted to hold a plurality 20 of brushes in engagement with one of said rings, a supporting member for said brush carriers, and means disposed thereon to longitudinally adjust said brush carriers.

3. In a current-collecting device, a plurality of collector rings, a plurality of arcuate-shaped brush carriers of conducting material, each adapted to hold a plurality 25 of brushes in engagement with one of said rings, a plurality of members adapted to support said brush carriers, and threaded means disposed thereon to longitudinally adjust said carriers and said brushes as a unit.

In testimony whereof, I have hereunto 30 subscribed my name this 30th day of Oct., 1918.

CHESTER B. MILLS.
